UNITED STATES PATENT OFFICE.

WILLIAM S. ELLIOTT, OF PITTSBURG, PENNSYLVANIA.

MOTOR.

983,034.

Specification of Letters Patent. Patented Jan. 31, 1911.

Application filed May 19, 1909. Serial No. 496,967.

To all whom it may concern:

Be it known that I, WILLIAM S. ELLIOTT, of Pittsburgh, in the county of Allegheny and State of Pennsylvania, have invented a new and useful Improvement in Motors, of which the following is a full, clear, and exact description, reference being had to the accompanying drawings, forming part of this specification, in which—

10 Figure 1 is a longitudinal section of one form of motor embodying my invention; Fig. 2 is a view partly in front elevation and partly in transverse section; Fig. 3 is a view similar to Fig. 1 showing a modification, and Fig. 4 is a section on the line IV—IV of Fig. 3.

My invention has relation to rotary motors, and is designed to provide a motor which shall be simple and compact in its 20 construction; and in which the parts are so constructed and assembled as to render them readily accessible as to renewal or repairs.

The nature of my invention will be best understood by reference to the accompanying drawings in which I have shown the preferred embodiments thereof, and which will now be described, it being premised, however, that various changes may be made in the details of construction and arrangement of parts without departing from the spirit and scope of my invention as defined in the appended claims.

In the drawings I have shown motors constructed in accordance with my invention 35 and especially adapted for use in operating boiler tube cleaning tools; but the motors may be used for a variety of other purposes.

In the drawings the numeral 2 designates an outer casing or shell formed at its front 40 and rear ends with the heads 3 and 4 respectively. When the motor is to be used for the purpose of operating boiler tube cleaning tools, the motor being carried through the boiler tubes with the cleaning 45 tools, the casing or shell together with the heads, are of cylindrical form, as shown; but for other purposes the shape of the casing or shell and heads may be modified as may be desired.

50 5 designates the shaft of the motor which is journaled in bushings 6 and 7; the bushing 6 has a flange 8 at its inner end seating forwardly against a shoulder 9 in the head 3.

10 55 10 designates the piston blade which is seated in the slot of the shaft 5 in the usual

manner and which rotates within the chamber of a cylinder 11 seated within the casing or shell 2. This cylinder has a piston chamber formed eccentrically therein, the ends of the cylinder being closed by the circular plates or disks 12 and 13. The disk 12 seats between the front end of the cylinder and the flange 8 of the bushing 6, while the disk or plate 11 seats between the rear end of the cylinder and the flange 14 at the inner end of the rear bushing 7. The bushing 7 is a split bushing and is seated in a cap member 15 which is provided with a space or chamber 16 at the rear of the bushing 7 to receive a head or collar 17 on the rear end of the shaft 5. This collar has a thrust bearing against the rear end of the bushing 7 to prevent any endwise movement to the shaft 5 in a forward direction; and the shaft has a shoulder 18 fitting against the inner end of the bushing 7 to take up end thrusts in the opposite direction. A space or chamber 19 is left behind the head or collar 17; and from this space a vent passage 20 extends obliquely through the cap 15 and connects at its outer end with a discharge opening 21 in the shell casing 2.

The head 4 has an internal thread 22 for engagement with the exterior thread of a socket member 23 screwed into said head 25 and having a threaded opening 24 for connection with a suitable supply pipe (not shown). The interior of the socket member and the rear end portion of the cap 15 are shaped to form an admission space or chamber 25 from which an admission port 26 leads forwardly through the cap member 15; the flange of the bushing 7, the plate or disk 13 and thence extends longitudinally through the thickened wall of the cylinder 11, which port communicates with the piston chamber by a plurality of cross ports 27.

28 is an exhaust port which is also formed in the thick portion of the wall of the cylinder and which extends forwardly through the plate or disk 12, the flange of the bushing 6 and the front head 3 being arranged to discharge at the front side of said head, This exhaust port communicates with a piston cylinder by a plurality of cross ports 29. The cylinder 11 may be conveniently held against rotation with the casing or shell by means of a pin or rivet 30. The inner head end 31 engages the longitudinal slot or recess 32 cut in the outer surface of the cyl-

105

110

inder. The end plates or disks 12 and 13, together with the bushings 6 and 7 are secured against rotation by the dowel pins 33.

The operation of the motor will be readily understood. Air or other motive fluid enters the admission chamber 25 and thence passes into the longitudinally extending admission port 26 into the piston chamber. The exhaust passes into the port 28 through the crossports 29 and is discharged at the front end of the motor. The provision of the space or chamber 19 and vent port 20 is for the purpose of preventing the accumulation of any back pressure at the rear end of the piston due to leakage of motive fluid through the rear shaft bearing.

The front end of the shaft 5 may be provided with a threaded shank 34 or other suitable means for the attachment thereto of the power tube cleaning tool or other device which is to be operated by the motor.

The parts can be readily assembled within the casing or shell; being readily and quickly secured in the proper relation by the means described. When the socket 23 is screwed into its seat into head 4, its inner end bears against the cap 15 and thereby effectively secures the parts against endwise movement against the casing or shell. By unscrewing the socket member, the parts may be readily removed for renewal or repairs.

In Figs. 3 and 4 I have illustrated my invention as applied to a tandem motor having the two cylinders 35 and 36 placed end to end, their inner ends being separated by the plate or disk 37 which forms the inner head of both cylinders. The longitudinally extending admission port 38 is common to and communicates with both cylinders, as does also the longitudinally extending exhaust port 39. 40 is a dowel pin of which any desired number may be employed which secures the two cylinders against rotary movement with respect to each other. 40^a designates other dowel pins engaging the opposite ends of the cylinders and the casing or shell, and which also hold the cylinders against rotation. In Fig. 3 the nozzle piece 23^a which corresponds to the nozzle piece 23 of Fig. 1 is shown as having an exteriorly threaded or corrugated shank 42^a for the reception of the flexible supply pipe or hose which is clamped thereon by means of a clamping sleeve 41 which is threaded into the extension 42 of the member 23^a. The shaft 5^a is provided with the two piston blades 10^a and 10^b, one within each of the two cylinders and the two blades being placed at an angle to each other. The general construction and manner of assembled and secured parts is similar to that shown in Fig. 1 and need not be further described in detail.

Various changes may be made in the details of construction and arrangement of the

several parts without departing from the spirit and scope of my invention; thus the shape of the exterior casing or shell may be changed; the manner of securing the cylinders and shaft bearings against rotary and endwise movements within said casing or shell may be varied and other mechanical changes may be made.

I claim:

1. A rotary motor comprising an outer casing or shell open at one end and having an integral head at the opposite end provided with a shaft bearing therein, an open-end cylinder removably seated in said casing or shell, wear plates or disks closing the ends of the cylinder, a removable head within the opposite end portion of the casing or shell and also having a shaft bearing, said head seating against the adjacent wear plate, a securing member engaging the removable head and holding it in place, and a piston shaft journaled in said heads and carrying a piston blade between the two wear plates, said wear plates, cylinder, removable head, and the piston shaft and blade being all removable through the open end of the casing or shell when the locking member is removed, substantially as described.

2. A rotary motor comprising an outer casing or shell open at one end and having an integral head at the opposite end provided with a shaft bearing therein, an open-end cylinder removably seated in said casing or shell, wear plates or disks closing the ends of the cylinder, a removable head within the opposite end portion of the casing or shell and also having a shaft bearing, said head seating against the adjacent wear plate, a securing member engaging the removable head and holding it in place, means for preventing rotary movement of the cylinder and of the removable head within the casing or shell, and a piston shaft journaled in said heads and carrying a piston blade between the two wear plates, said wear plates, cylinder, removable head and the piston shaft and blade being all removable through the open end of the casing or shell when the locking member is removed, substantially as described.

3. In a rotary motor, an outer casing or shell having an integral head at one end, and a removable head held within its opposite end portion, said heads having shaft bearings, a cylinder removably held within the casing or shell between the heads, a piston shaft extending through the cylinder and journaled in the heads, a piston blade carried by said shaft, and a wear plate at each end of the piston, substantially as described.

4. In a rotary motor, an outer casing or shell, having an integral head at one end, and a removable head within its opposite end, said heads having each a shaft-bearing bushing therein and said bushings having

each a flanged inner end, a piston shaft journaled in said bushings and carrying a blade, a cylinder within the casing between the flanges of the bushings, and a wear plate seated at each end of the blade between the end of the cylinder and the flange of the adjacent bushings, substantially as described.

5. In a rotary motor, an outer casing or shell, having an integral head at one end, and a removable head within its opposite end, said heads having each a shaft-bearing bushing therein and said bushings having each a flanged inner end, a piston shaft journaled in said bushings and carrying a blade, a cylinder within the casing between the flanges of the bushings, and a wear plate seated at each end of the blade between the end of the cylinder and the flange of the adjacent bushings, the casing or shell being open at the end having the removable head, and all the parts contained within the casing being removable through such open end, substantially as described.

6. In a rotary motor, an outer casing or shell, having an integral head at one end, and a removable head within its opposite end, said heads having each a shaft-bearing bushing therein and said bushings having each a flanged inner end, a piston shaft journaled in said bushings and carrying a blade, a cylinder within the casing between the flanges of the bushings, a wear plate seated at each end of the blade between the end of the cylinder and the flange of the adjacent bushings, and dowel pins seated in the said heads and also extending through the wear plates into the end portions of the cylinder, substantially as described.

7. In a rotary motor, an outer casing or shell, having an integral head at one end, and a removable head within its opposite end, said heads having each a shaft-bearing bushing therein and said bushings having each a flanged inner end, a piston shaft journaled in said bushings and carrying a blade, a cylinder within the casing between the flanges of the bushings, a wear plate seated at each end of the blade between the end of the cylinder and the flange of the adjacent bushings, and dowel pins seated in the said heads and also extending through the wear plates into the end portions of the cylinder, together with means for preventing the cylinder from rotating within the casing or shell, substantially as described.

8. A rotary motor, comprising a portable casing, or shell, having an integral head at its front end and open at its rear end, a removable head within the rear portion of the casing or shell, shaft bearings carried by the said heads, a piston shaft journaled in said heads, an open-end cylinder within the casing or shell between the two heads, wear and thrust members between the ends of the cylinder and the heads, said shaft having a re-

duced journal portion in the rear head with a thrust shoulder at each end of said journal, substantially as described.

9. In a rotary motor, a portable outer casing or shell, having an integral head at one end, and open at the opposite end, and having at least one open end, a cylinder removably seated therein, another head removably seated and held in the casing or shell, and a plurality of wear plates closing the ends of the cylinder or cylinders, all the parts contained within the casing or shell being removable through the open end thereof, substantially as described.

10. In a portable rotary motor, a portable outer casing having an integral head at its forward end, and open at the rear end, a motor cylinder removably seated in said casing and removable through the open rear end, means for holding the cylinder from rotary movement within the casing, a motor shaft having a forward bearing in the integral head, a motor element connected to said shaft, and a removable bearing and admission member having a bearing for the rear end of the shaft, said shaft, motor element and rear bearing all being removable through the rear end of the casing, together with means for normally securing said parts against endwise rearward movement; substantially as described.

11. A rotary motor comprising an outer casing or shell having an integral head at one end carrying a shaft bearing, said shell being open at the other end, a cylinder inserted in the casing from the open end thereof and secured against rotation, a stationary ported admission member inserted through the open rear end of the outer casing, and a rotary motor element within the cylinder, substantially as described.

12. A rotary motor comprising an outer casing or shell having an integral head at one end carrying a shaft bearing, said shell being open at the other end, a cylinder inserted in the casing from the open end thereof and secured against rotation, a stationary ported admission member inserted through the open rear end of the outer casing, a rotary motor element within the cylinder, and a removable bearing in the rear of the rotary motor element and removable through the rear of the casing, substantially as described.

13. A rotary motor comprising an outer portable casing or shell having a bush bearing carried at one end thereof, and of smaller diameter than the casing, said shell being open at the other end, a cylinder inserted in the casing from the open end thereof and secured against rotation, a stationary ported admission member inserted through the open rear end of the outer casing, means for securing said member in place, and a rotary motor element within the cylinder.

14. A rotary motor, comprising an outer

- casing or shell open at one end and having an integral head at the opposite end provided with a shaft bearing therein, an open-end cylinder removably seated in said casing or shell, a removable head within the opposite end portion of the casing or shell, and also having a shaft bearing, a securing member engaging the removable head and holding it in place, and a piston shaft journaled 10 in said heads and carrying a piston blade, said cylinder, removable head and piston shaft and blade being all removable through the open end of the casing or shell when the securing member is removed.
15. 15. A rotary motor comprising an outer casing or shell having an integral head at

one end carrying a shaft bearing, said shell being open at the other end, a cylinder inserted in the casing from the open end thereof and secured against rotation, a stationary 20 ported admission member inserted through the open rear end of the outer casing, a rotary motor element within the cylinder, and means for locking the stationary ported admission member in place.

25 In testimony whereof, I have hereunto set my hand.

WILLIAM S. ELLIOTT.
